UNITED STATES PATENT OFFICE.

JOHN H. JOHNSTON, OF NEW YORK, N. Y.

DESIGN FOR A SPOON, &c.

SPECIFICATION forming part of Design No. 20,668, dated April 7, 1891.

Application filed March 16, 1891. Serial No. 385,286. Term of patent 7 years.

To all whom it may concern:

Be it known that I, JOHN H. JOHNSTON, a citizen of the United States, residing at New York city, in the county of New York and State 5 of New York, have invented a certain new and ornamental Design for Spoons, of which the following is a description.

The design is represented in the accompanying drawing, which shows a spoon having 10 a conventional bowl and a stem or handle extending from it. On the end of the handle, and constituting a prolongation of it, is a bust representation of a person. In this particular instance the person represented is General 15 Sherman. The coat he wears is a regulation military coat, and the lower edge of the figure is bounded by sprays of laurel and oak. The bust appears to be protruding from the folds of the American flag, which is wrapped around 20 upon itself, forming a sort of elongated cornucopia constituting the stem of the spoon. The stars and stripes of the flag are both visible, and the folds are entwined with oak and laurel, which appear at the base of the handle 25 and about midway of its length. The hilt of

a sword appears protruding from the upper edge of the flag and stands in front of the lower edge of the bust.

In the drawing, A represents the bowl of the spoon; B, the stem extending therefrom; 30 C, the bust representation; b b, the folds of the flag; a, the hilt of the sword, and c c the sprays of laurel and oak.

The salient feature of the design is the bust of the person, such as an officer in the army 35 or navy, coupled with the flag.

It seems that the design needs no further description, as the general appearance and detail are obvious from the drawing.

I claim as my invention and desire to secure by Letters Patent— 40

The design for spoons herein described and illustrated.

In witness whereof I have hereunto signed my name in the presence of two subscribing 45 witnesses.

JOHN H. JOHNSTON.
